ARCUATE RADIO TUNING INDICATOR FACEPLATE

Maurice D. Katz, 35 Broadway, Lawrence, N.Y. 11559

Filed May 18, 1971, Ser. No. 144,708

Term of patent 14 years

Int. Cl. D14—03

U.S. Cl. D26—1

FIG.1

FIG.2

FIG. 1 is a perspective view of an arcuate radio tuning indicator faceplate showing my new design; and

FIG. 2 is a perspective view thereof, installed in a radio.

The broken lines are shown for illustrative purposes only.

I claim:

The ornamental design for an arcuate radio tuning indicator faceplate, substantially as shown and described.
